United States Patent Office.

L. A. SUNDERLAND, OF MADISON, OHIO.

Letters Patent No. 101,784, dated April 12, 1870.

IMPROVEMENT IN MILK-CANS.

The Schedule referred to in these Letters Patent and making part of the same

To all whom it may concern:

Be it known that I, L. A. SUNDERLAND, of Madison, in the county of Lake and State of Ohio, have invented certain new and useful Improvements in Milk-Cans; and I do hereby declare that the following is a full and complete description of the same, reference being had to the accompanying drawing making a part of this specification, in which—

Figure 1 is a perspective view.

Figure 2 is a section showing the bottom of the can.

Like letters refer to like parts.

The nature of this improvement relates to the construction of a can for holding milk while being transported, and is so devised that there is no springing of the bottom, whereby a can, as usually constructed, soon wears out and becomes useless, or requires frequent repairing.

In the drawings—

A represents the body of a can, which may be made of tin of suitable weight, according to the size or capacity of the can.

B represents the bottom, which is made as follows:

A piece of sheet-iron, of sufficient thickness to give the required strength, is pressed in a concave form, and having a flange, b, turned at the edge. This bottom is made of heavier plate than tin plate, and after being formed is trimmed.

A hoop or band, C, is also provided.

The bottom B being placed in the body A, and the hoop set on as represented, they are riveted together, making a very strong and unyielding can. The inside is then soldered, as also is the outside.

The bottom B may be put in the other side up, but this way is preferable, as it makes an arch capable of much resistance.

The bottom is held by the rivets, and does not depend upon the solder for that purpose. The solder only makes a water-tight joint.

By this mode of construction a much cheaper can is made, and is fully as desirable, and more easily made than my patents formerly granted.

What I claim as my improvement, and desire to secure by Letters Patent, is—

As a new article of manufacture, a can provided with a convex-flanged bottom, B, made in one piece, the flange b not extending below the bottom of the can, and having a hoop, C, on the outside, the hoop, body, and flanged bottom being riveted together, as set forth.

L. A. SUNDERLAND.
